UNITED STATES PATENT OFFICE

FRANK S. TRUSLER, OF VERNON, TEXAS

ARTIFICIAL TOOTH

Application filed February 2, 1929. Serial No. 336,968.

This invention relates to an improved artificial tooth of the species embodying a porcelain facing and a metallic backing plate, together with a separable interlocking connection or coupling between the plate and facing.

One distinguishable refinement embodied in the improved structure is a porcelain facing having an appropriately shaped extension at one end, properly colored as to function for a gum shield and further functioning to provide a successful and comfortable connection of the facing with the natural gum in a manner to conceal defects in the gum from shrinkage.

A further feature is the backing plate having an extension at one end laterally arranged to facilitate mounting on a bridge.

The predominating distinction is predicated upon the provision of an improved joint or coupling between the backing plate and facing, this embodying a cavity formed in the facing, and a coupling pin formed integrally on the backing plate for telescopic reception in the cavity, the pin having acute angular relationship with respect to the longitudinal axis of the backing plate to distribute strain and to prevent accidental shearing off of the pins from the direct biting pressure exerted upon it, when it is in use.

Other features and advantages of the invention will become more readily apparent from the following description and drawings.

In the drawings:

Figure 1 is a side or edge elevational view of a complete artificial tooth constructed in accordance with the present invention.

Figure 2 is a view in section and elevation showing the assemblage more precisely.

Figure 3 is a face view of the metallic backing plate and its coupling pin.

Figure 4 is a sectional view, taken approximately upon the plane of the line 4-4 of Figure 2.

The entire tooth is generally designated by the reference character 5 and as before indicated, it comprises a suitably shaped porcelain casing 6, and a backing plate 7. These parts of course vary in configuration according to the particular point of place-

ment in the mouth. The facing has an extension 8, functioning as a natural gum shield and appropriately shaped and colored to provide a successful joint between the facing and the gum and to conceal the shrivelled portion of the gum. The facing is also provided with an angularly disposed vertically elongated cavity, telescopically receiving the correspondingly shaped and arranged coupling pin 9 on the central portion of the backing plate. This pin is substantially ovate in cross section, as shown in Figures 3 and 4. Moreover, it is inclined with respect to the longitudinal axis of the plate and in fact assumes a somewhat acute angular relationship to the plate. The upper half portion is comparatively longer than the lower half portion, thus giving the pin the substantially wedge shaped configuration observed in Figure 2. The advantage of this acute angular relationship over a true right angular relationship is to relieve the pin of shearing strain and to provide a more dependable and rigid joint. The pin is also formed on opposite sides with longitudinally formed toothed ribs 10, functioning as keys and extending into key ways formed in the opposite side walls of the cavity in the facing as shown in Figure 4. When the parts are connected together, as shown in Figure 2, (cement, not shown), it is obvious that a wedge like action is produced, firmly binding the plate and facing together and equalizing the strain and thus rendering the joint more steady and dependable in action.

At one end of the backing plate is a lateral extension 11, for connection with bridge work and at the opposite end is a laterally offset thickened biting edge 12.

A careful consideration of the description in conjunction with the drawings will convincingly show the reader that I have evolved and produced a structure which, it is believed, will supersede similar artificial tooth constructions and a structure which, it is believed, has been previously unequalled in the art or the trade, something which is practical and modern and will fulfill the requirements of an invention of this class in a highly satisfactory manner.

A more specific description of the invention is regarded unnecessary.

Minor changes in the size, shape and materials coming within the field of invention may be resorted to, in actual practice, if desired.

I claim:

1. In an artificial tooth construction of the class described, a facing having a longitudinally elongated cavity extending inwardly and inclined downwardly from one side of the facing, and a backing plate disposed in contact with said facing at said one side and having a correspondingly shaped coupling pin fitted into said cavity, said coupling pin being disposed at an acute angle to the longitudinal axis of the backing plate, and a plurality of longitudinally spaced downwardly and forwardly extending toothed ribs formed on the opposite longitudinal sides of said pin and keyways formed in the opposite longitudinal sides of the cavity for receiving said ribs.
2. As a new product of manufacture, a backing plate having one end thickened and laterally offset to provide a biting surface and having the opposite end laterally disposed to facilitate connection with bridge work, said plate on one side thereof being provided with an elongated coupling pin having on opposite longitudinal sides thereof a plurality of longitudinally spaced inclined toothed anchoring ribs.
3. In an artificial tooth of the class described, a facing having a cavity, and a backing plate having a connecting pin fitting conformably within said cavity, said connecting pin embodying a relatively long upper edge inclining downwardly and outwardly from said backing plate and at its outer end merging into a downwardly and inwardly inclined vertical edge which in turn at its lower end merges into the lowermost end of the lower edge of said pin, said lower edge inclining downwardly from said plate and being of a length shorter than the upper edge of said pin, and a plurality of longitudinally extending vertically spaced anchoring ribs on opposite vertical sides of said pin inclining downwardly and outwardly toward the outer inclined edge of said pin.

In testimony whereof I affix my signature.

FRANK S. TRUSLER.
